UNITED STATES PATENT OFFICE.

JOHN H. FREDERICKS, OF LOCK HAVEN, PENNSYLVANIA, ASSIGNOR OF ONE-HALF TO THE ST. LOUIS STAMPING COMPANY, OF ST. LOUIS, MISSOURI.

COOKING UTENSIL.

SPECIFICATION forming part of Letters Patent No. 397,847, dated February 12, 1889.

Application filed January 16, 1889. Serial No. 296,499. (No model.)

To all whom it may concern:

Be it known that I, JOHN H. FREDERICKS, a citizen of the United States, residing at Lock Haven, in the county of Clinton, State of Pennsylvania, have invented certain new and useful Improvements in Cooking Utensils; and I hereby declare the following to be a full, clear, and exact description of the same.

My invention relates to an improvement in cooking utensils, and has for its ultimate object the protection of the contents of the utensil during the process of cooking from scorching by reason of the undue application of heat, and the immediate object is to provide a cooking utensil having these characteristics of a more economical and desirable construction than has heretofore been found practicable.

It has been suggested that the scorching of the contents of the cooking utensil during the process of cooking can be prevented by providing the article with a double bottom and interposing therein a non-combustible material—such as magnesium powder, &c., or asbestos fiber. In all constructions with which I am acquainted, however, it has been deemed necessary to interpose the non-combustible material loosely, requiring special manipulation of a laborious and expensive character in the construction of the article. Thus, when the powder was employed, the lower bottom was first filled, then applied to the upper bottom, and the parts joined by hand or a manual tool. Where asbestos fiber has been employed the same operation has been deemed necessary, the material being interposed in loose strips or sheets between the upper and the lower bottom. There are two pronounced objections to this mode of manufacture. In the first place, the loose material is found to be liable to become displaced in the handling of the ware, whereby certain parts of the bottom or lower sides of the ware present no protection against the scorching heat. In the second place, the delay in the process of manufacturing the article necessary to permit the interposition of loose non-combustible material is so great as to involve a material increase in the cost of manufacture. I overcome these difficulties by the construction and method hereinafter described, although I wish it understood that in this specification I mean

to claim only the article of manufacture, which, as will readily appear, can be produced by other methods than the one herein-after set forth.

My invention consists in a culinary vessel provided with a double bottom and having interposed between the bottoms a sheet of non-combustible material secured at its circumferential edges between the circumferential edges of the double bottom and the vessel.

My invention further consists in a vessel of this character having a double bottom and double sides for a short distance above the bottom, presenting a continuous chamber and having interposed between said double bottoms and sides a single sheet of incombustible material secured at its circumferential edge between the upper edge of the outer double side and the vessel.

In the drawings, Figure 1 is a vertical sectional view of a cooking utensil made in accordance with my improvement, in which the incombustible material is applied in a single sheet to the bottom only. Fig. 2 is a similar view showing the incombustible material applied to the bottom and lower sides.

A represents the body of the vessel, having an integral bottom, D.

B is the lower bottom, which may be extended to produce an outer or double side, as shown in Fig. 2.

C represents a sheet of asbestos or similar incombustible material, which may or may not be provided with perforations, in the usual manner. The bottom B may be secured to the vessel A either by riveting or soldering the same; but, as shown in the drawings, it is preferably secured by spinning.

In producing the article a sheet of asbestos of suitable size is stamped to the proper shape at the same time that the other parts of the vessel—to wit, the body A and lower bottom, B—are formed, and the parts thereupon adjusted together and riveted, brazed, spun, or otherwise secured at the edges of the double bottom and asbestos. When rivets are employed, they may pass through the asbestos, or the latter may be jammed at its edges between the double bottom B and the vessel A immediately below the rivets or other fastening medium. In this manner the interposed

protecting medium is at all times firmly secured in place and the increased cost of interposing the protecting medium is reduced to the minimum. When the lower bottom is secured upon the vessel by spinning, the interposed material is secured at its edges during the same spinning operation that secures the double bottom to the vessel.

What I claim as new, and desire to secure by 10 Letters Patent, is—

1. As a new article of manufacture, a culinary vessel having a double bottom and having an interposed sheet of non-combustible material secured at its circumferential edge

between the lower bottom and the vessel, as 15 described.

2. As a new article of manufacture, a culinary vessel provided with the double bottom and double lower sides and having an interposed sheet of non-combustible material secured at its circumferential edge between the double side and the vessel and covering the bottom and part of the sides of the latter, substantially as described.

JOHN H. FREDERICKS.

In presence of—

E. A. HONAGHAN,
T. C. CARSON.
